DESIGN FOR A COMBINATION BACK AND ARM REST FOR A COUCH OR SIMILAR ARTICLE OF FURNITURE

Gustave A. Johnson, Weymouth, Mass., assignor
to New England Bedding Company, Medford,
Mass., a corporation of Massachusetts

Application March 13, 1936, Serial No. 61,621

Term of patent 14 years

To all whom it may concern:

Be it known that I, Gustave A. Johnson, a citizen of the United States of America, residing at Weymouth, in the county of Norfolk and Commonwealth of Massachusetts, have invented a new, original, and ornamental Design for a Combination Back and Arm Rest for a Couch or Similar Article of Furniture, of which the following is a specification, reference being had to the accompanying drawing, forming a part thereof.

Fig. 1 is a perspective view of a combination

back and arm rest for a couch or similar article of furniture, showing my new design; and

Fig. 2 is an end elevation thereof.

I claim:

The ornamental design for a combination back and arm rest for a couch or similar article of furniture, as shown.

Signed by me at Medford, in the county of Middlesex and Commonwealth of Massachusetts, this 11th day of March, 1936.

GUSTAVE A. JOHNSON.
